UNITED STATES PATENT OFFICE

JOSEPH BECKER, OF PITTSBURGH, PENNSYLVANIA, ASSIGNOR TO THE KOPPERS COMPANY OF DELAWARE, A CORPORATION OF DELAWARE

METHOD OF PROVIDING FUEL GAS FOR COOKING RETORT OVENS

Application filed February 19, 1929. Serial No. 341,240.

My invention relates to heating systems for coking retort ovens and particularly to means for utilizing blast-furnace gases for heating the oven chambers of coking retort ovens.

An object of my invention is to provide means whereby blast-furnace gases from one or a plurality of sources may be utilized more effectively and economically as fuel gas for underfiring coke-oven batteries.

10 My invention has also for its further objects such other advantages and improvements as may be found to obtain with respect to it as hereinafter described or claimed.

In the operation of coke-oven batteries, it is very essential that the B. t. u. value of the fuel gas be substantially uniform inasmuch as the relative quantity of air, that is, in proportion to that of gas, is ordinarily limited by flow conditions that have to be maintained.

20 However, a variation in the B. t. u. value of the gas correspondingly changes the amount of air required for perfect combustion. If the gas exceeds the normal B. t. u. value, the quantity of air is insufficient and imperfect

25 combustion results. If the gas is too lean, there is a surplus of air and the result is to cool the ovens by reason of the heat required to bring the excess air up to the temperature of the gases of combustion.

30 The supplying of fuel gas at a definite B. t. u. value insures a uniform application of heat to the coking mass, with the result that a uniform coke is produced from any good coal and uniformity and regularity of coking operations is secured.

35 In the normal operation of a coke plant in which a part of the coke-oven gas that is produced is used as fuel gas to heat the ovens, the coke-oven gas has an average thermal value of 530' B. t. u. The variation in the thermal value of the gas does not exceed more than approximately 15 B. t. u.'s, representing a fluctuation of about 3%. This percentage of variation is so small that from a practical standpoint it is not necessary to provide means for maintaining the B. t. u. value constant at any predetermined value. The regulation of the B. t. u. value of coke-oven gas might be accomplished by supplying the small amount of air or inert gas needed

to maintain the thermal value at the minimum B. t. u. value of the coke-oven gas.

Lean gas is especially suitable for underfiring coke-oven batteries because of the readily obtained uniform vertical distribution of the heat of combustion, since the combustion of such gas tends to occur throughout substantially the entire length of the flame flues. When gas of this character is employed as a fuel, the quality of coke averages 60 very high because of the uniform heating conditions throughout the vertical height of the ovens.

In the operation of blast furnaces in connection with steel mills and other similar plants, considerable gas is generated that may be utilized as a fuel gas but which is of very low B. t. u. value. By reason of the methods of operation of blast furnaces, the gas varies widely in B. t. u. value, not only from day 70 to day but many times during the same day. The B. t. u. value of the gas may vary from approximately 85 to 110, a variation of approximately 25%.

75 In order to utilize blast-furnace gas as a fuel for heating coke ovens, it is very essential that the blast-furnace gas be corrected to such degree of uniformity of B. t. u. value that the coking results are comparable with those of operation with coke-oven gas, even though coke-oven gas is effectively used without correction of its thermal value. Otherwise, the coking time required for any given coal is unduly prolonged and made irregular by the loss in heat when the B. t. u. value of the blast-furnace gas is below its maximum value.

80 It may be assumed that a coke plant has a coking time of 16 hours when the ovens are heated with coke-oven gas. If, when heated with blast-furnace gas, there be a variation in the B. t. u. value of the gas such that there is a delay of even only 15%, such delay would be equivalent to 2.4 hours. If the plant had a normal carbonizing capacity of 1000 tons, the reduction of coking capacity would amount to 90 150 tons. It will be readily seen that such fluctuations may be of such importance as to defeat the effective or economic use of blast-furnace gas in coke ovens.

95 The manual regulation of very lean gas, 100

such as blast-furnace gas, is very difficult since it is not practicable to determine by mere visual inspection whether the combustion is normal, the combustion occurring substantially without visible flames, and the variations of B. t. u. value in the blast-furnace gas may be too large and frequent.

I have found, however, that blast-furnace gas from one or more sources and that is even highly variable in its B. t. u. value may be used with high efficiency to produce coke of high and uniform quality, by providing means for insuring a constant B. t. u. value of the gas. In general, the B. t. u. value of the gas is regulated by means of a calorimeter which controls a valve to admit more or less coke-oven gas to correspondingly vary the B. t. u. value of the blast-furnace gas, thereby insuring a constant B. t. u. value for the mixture.

When blast-furnace gas is used in the manner above stated, the coke-oven battery will operate smoothly and efficiently. When so used, blast-furnace gas is at least the equal of coke-oven gas as a fuel for heating coke ovens. The coke produced is of very high quality because of the uniform vertical distribution of the combustion of the fuel gas and the short coking time and regular coking schedule may be maintained by maintaining a uniform inflow of heat into the coking mass in all the ovens of the battery.

Also, if the blast furnaces be supplied with coke from ovens underfired with blast-furnace gas of regulated B. t. u. value, the operation of the blast furnaces becomes more nearly constant, due to the use of uniform coke, and, consequently, the variations in the B. t. u. value of the blast-furnace gas are materially diminished. When such use of blast-furnace gas and such use of coke from the ovens so fired is employed, there results a considerable decrease in the fluctuations of the blast-furnace gas, with a resultant decrease in the quantity of coke-oven gas that is required to be utilized by the regulating apparatus.

An important economy is effected by the use of blast-furnace gas for fuel purposes in that it releases valuable coke-oven gas for use as heating gas for commercial or domestic purposes. For example, in the production of a ton of pig iron, approximately one ton of coke is used, with the production of about 130,000 cu. ft. of blast-furnace gas with a thermal value of about 90 B. t. u. per cu. ft. The normal amount of 530 B. t. u. coke-oven gas required to carbonize coal to produce one ton of coke is 6400 cu. ft. This carbonization may be effected by about 40,000 cu. ft. of the 90 B. t. u. blast-furnace gas and thus release the 6400 cu. ft. of much more valuable coke-oven gas for other purposes for which blast-furnace gas is wholly unsuitable.

When the relatively lean blast-furnace gas is employed as a fuel, the volume of the

gases of combustion is greater than that when richer gas is employed. However, by reason of the regulation of the blast-furnace gas to its maximum B. t. u. value, only a slight increase in the cross-sectional dimensions of certain of the passageways of the battery is necessary to accommodate the flow of products of combustion therethrough.

The details of an illustrative embodiment of my invention will be described in connection with the accompanying drawings, in which

Figure 1 is a plan view of a coke-oven plant and associated apparatus for supplying blast-furnace gas to the coke-oven plant in accordance with my invention;

Fig. 2 is a view in transverse vertical section of a coke-oven battery adapted to use blast-furnace gas as a fuel;

Fig. 3 is a longitudinal vertical sectional view of such battery on the section lines indicated in Fig. 2;

Fig. 4 is a plan view of a mixing device, parts being broken away; and

Fig. 5 is a view in transverse section taken along the line V—V of Fig. 4.

Referring particularly to Fig. 1, a coke-oven plant comprising a battery 1 of coking retort ovens is adapted to be supplied with fuel from a source of blast-furnace gas comprising a blast furnace 2. The gas from the blast furnace 2 flows through a pipe 3, scrubbers 4 and boosters 5 to a gas holder 6 of any usual or suitable construction.

Gas from the holder 6 flows through a pipe 7, a mixing device 8 and pipes 9, 10, and 11 to the distributing mains 12 and 13 of the battery 1. The collecting main 15 of the battery 1 is connected by a pipe 16 to the usual scrubbers 17 and boosters 18 for cleaning the gas and for increasing its pressure for conducting it through a pipe 19 to any suitable storage device (not shown). A branch pipe 20 connects the pipe 19 through a pipe 21, a meter 22 and a pipe line 23 to the mixing device 8 for a purpose to be hereinafter described.

A calorimeter 24 of standard construction for measuring the thermal value of gas supplied thereto, and provided with a burner adapted to serve for blast-furnace gas, is connected by a pipe 25 to the pipe 9 which supplies fuel gas to the battery 1. An electrical measuring device 26, which is also of standard construction, is connected to the calorimeter 24 and controls the electrical connections of an electric motor 27 that operates a butterfly valve 28 in the pipe line 23.

Reference may now be had to Figs. 2 and 3, in which are illustrated certain of the details of a coking retort oven battery of the Becker regenerative type that are arranged to be operated either with coke-oven gas or blast-furnace gas for heating the ovens. The battery comprises a foundation 30 immedi-

ately above which are located the regenerators 31 and 32 which extend transversely or cross-wise of the battery for half the width of the latter.

5 Above the regenerators 31 and 32 are a series of oven chambers 33 which alternate with heating walls 34, the outer surfaces of which constitute the sides of the oven chambers 33. Brickwork 35 constitutes a floor for the oven chambers and a roof for the regenerators 31 and 32. The battery is provided with a top 36, through which extend charging openings 37 for the introduction of coal to be coked and through which extend also crossover flues 38 for connecting the flame flue systems of adjacent heating walls 34.

20 Each heating wall 34 is provided with a series of flame flues 39 that are connected to the regenerators 31 and 32, as the case may be, by inclined ducts 40 and 41. Each flame flue is also provided with a nozzle 42 through which coke-oven gas may be supplied from gas guns 43. At their tops, the flame flues 39 are each connected by a duct 44 to a horizontal flue 45 which extends substantially the length of the heating wall. The horizontal flues 45 are connected by six crossover flues 38.

25 30 Each of the oven chambers 33 is provided with an off-take opening 47 to which is connected an ascension pipe 48 and the collecting main 15 for conducting the gases and other products of distillation from the battery. The distributing mains 12 and 13 for supplying blast-furnace gas to the battery are disposed along the respective sides of the battery and are connected to the sole flues 49 and 50, respectively, of the regenerators 31 and 32 by means of valve mechanisms 51 and 52.

35 40 The battery 1 is also supplied with mains 53 and 54 for supplying coke-oven gas to the flame flues of the heating walls 34, through the gas guns 43 that extend through the brickwork 35.

45 50 When the coke-oven battery is especially adapted for blast-furnace gas operation, the horizontal flues 45, crossover flues 38 and certain of the ducts 44 are slightly enlarged as compared with the dimensions for producer gas operation, other ducts 44 being enlarged to a greater extent. The ducts 40 and 41 are not enlarged but the usual "banana" bricks 54a at the bottoms of the flues 39 are removed. The gas mains 12 and 13 may be slightly larger but if producer gas and blast-furnace gas requirements fall between the same standard sizes of pipe, they would be the same in each case.

55 60 It should be understood, however, that a coke-oven battery adapted for blast-furnace gas is equally well adapted for producer gas since the latter is of somewhat higher thermal value and accordingly the volume of combustion products is smaller. The coke-

oven battery shown and described herein is therefore adapted for operation with either blast-furnace gas, producer gas or coke-oven gas.

65 70 The details of the mixing device 8 are shown in Figs. 4 and 5. The pipe 7, for introducing blast-furnace gas from the holder 6 to the battery 1, is surrounded by an annular header 55, to which is connected the pipe line 23 and by means of which the header is supplied with coke-oven gas from the main 19. The header 55 is connected to the interior of the pipe 7 by means of a series of radially-extending pipes 56 and 57 that are of different lengths and which, accordingly, extend into the pipe 7 different distances. Accordingly, when gas enters the pipe 7 from the mixing device 8, it is thoroughly distributed with the blast-furnace gas traversing the latter to produce a substantially uniform mixture.

75 80 In the operation of the heating system described above, the blast-furnace gas from the blast furnace 2 may vary in thermal value from approximately 85 to 110 B. t. u.'s. The holder 6 may be and is in practice of relatively small capacity. A small holder is possible because correction of the blast furnace renders it unnecessary to employ a large holder to at least partially equalize the inequalities of the supply of gas from the blast furnace 2 or other blast furnaces before it is supplied to the battery 1.

85 90 As the gas flows through the pipe 7 and the various pipes and distributing mains to the battery, a relatively small amount flows through the pipe 25 to the calorimeter 24 which measures the thermal value of the gas as it is delivered to the battery. The calorimeter translates the B. t. u. value thus measured to the electrical unit 26, a movable member of which operates in accordance with the measurement thus obtained to control the electric motor 27 and the latter adjusts the butterfly valve 28 to admit more or less-coke-oven gas to the pipe line 23.

95 100 105 This gas passes through the mixing device 8 and the quality of the blast-furnace gas is thus varied or corrected to the predetermined value for which the calorimeter 24 is adjusted. This predetermined value is preferably the maximum value of the blast-furnace gas when it is not corrected. A higher predetermined value may be selected but it is obvious that such value requires more coke-oven gas to maintain the higher thermal value of the corrected gas. The result is to supply the battery 1 with blast-furnace gas that has been corrected to a substantially constant value of approximately 110 B. t. u.'s.

110 115 120 A pipe 58, having a valve 59, is provided for use in case it is necessary or desirable to by-pass the gas holder 6. Valves 60 and 61 control the connections to the holder 6 and will, of course, be closed when the by-pass pipe 58 is used.

A pipe 62 may be employed when necessary or desirable to by-pass the meter 22, suitable valves being provided for the respective connections.

While my invention has been described in connection with a single blast furnace as a source of supply of blast-furnace gas, it is obvious that any desired number of blast furnaces may be so employed. Also, while the 10 heating system has been shown and described in connection with a single coke-oven battery, the arrangement may be extended by similar connections from the pipe 9 to other batteries of the plant, one of such batteries 63 being 15 indicated by dot-and-dash lines.

My invention has for its advantages the employment of a relatively cheap fuel gas of very low thermal value that is unsuitable for the many purposes for which coke-oven gas 20 may be utilized. Inasmuch as the blast furnaces and coke ovens are often adjacent to each other particularly in steel plants, the utilization of the blast-furnace gas in accordance with my invention constitutes an extremely 25 convenient and economical arrangement.

While I have shown and described my invention in its preferred form, it is obvious that modifications may occur to those skilled 30 in the art relating to the operation of coke-oven plants. Accordingly, the scope of my invention is not limited to the particular embodiment shown herein except as expressed in the claims.

35 I claim as my invention:

1. The method of providing fuel gas for coking retort ovens which comprises supplying blast-furnace gas of variable thermal value, mixing a relatively small amount of 40 coke-oven gas with said blast-furnace gas to correct the thermal value of the latter when it falls below a predetermined value, measuring the thermal value of the gases so mixed, and then regulating the amount of coke-oven 45 gas added to said blast-furnace gas in accordance with the measurement thus obtained to maintain the thermal value of the mixed gas substantially constant at approximately the maximum thermal value of the blast-furnace 50 gas.

2. The method of providing fuel gas for coking retort ovens which comprises supplying blast-furnace gas of variable thermal value, mixing a relatively small amount of coke-oven 55 gas with said blast-furnace gas to correct the thermal value of the latter when it falls below a predetermined value, measuring the thermal value of the gases so mixed, causing the measured thermal value thus obtained to control the amount of coke-oven gas so mixed with the blast-furnace gas to maintain said measured value substantially constant, and then supplying the mixed gas to said ovens for combustion therein.

3. The method of providing fuel gas for cok-

ing retort ovens having flame flues which comprises supplying blast-furnace gas that is variable between minimum and maximum thermal values, mixing a relatively small amount of coke-oven gas with said blast-furnace gas, measuring the thermal value of the gases so mixed, employing the measured value thus obtained to control the amount of coke-oven gas added to said blast-furnace gas to maintain the mixed gas substantially constant at the maximum thermal value of the blast-furnace gas and then supplying the mixed gas to said flame flues.

In testimony whereof, I have hereunto subscribed my name this 18 day of February 1929.

JOSEPH BECKER.
